(57) **CLAIM**

The ornamental design for a rack for storage as shown and described.

DESCRIPTION

FIG. 1 is a front, right and bottom perspective view of a rack for storage, showing our design;

FIG. 2 is a rear, left and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another front, right and bottom perspective view thereof in an environment of use.

The broken lines shown in FIGS. 2, 5 and 6 illustrate portions of the rack for storage that form no part of the claimed design. The broken lines in FIG. 9 are environment that form no part of the claimed design.

1 Claim, 9 Drawing Sheets
